DEVICE FOR TYING THREAD ENDS IN WIND-
ING FRAMES OR OTHER TEXTILE MA-
CHINESStefan Fürst, Gladbach-Rheydt, Germany; vested
in the Alien Property CustodianApplication February 18, 1941, Serial No. 379,542
In Germany July 14, 1939

5 Claims. (Cl. 289—3)

In order to tie the ends of the running on and running off threads together by a weaver's knot, it has heretofore been the practice to start by forming one of the ends to be tied into a loop with crossed arms. This loop was then laid around a support shiftable in its axial plane and an auxiliary loop was formed by means of a thread guide through which auxiliary loop the other thread end was pulled. The thread guide was then moved out of the first auxiliary loop with formation of another auxiliary loop without crossing of the thread arms, whereupon the auxiliary loop was undone and the knot pulled together after the tie has been liberated by the supporting element. This tying procedure was very complicated and accordingly the arrangement for carrying it out mechanically was also.

According to the invention the tying procedure is considerably simplified, so that the knotted bills generally used successfully in hand-operated implements can be used for carrying it out.

The tying proceeding takes place, according to the invention, in that the threads are laid non-crossed into the bend of the knotter bills of a knot forming device, with their ends pointing in opposite directions, the bights and ends of the two threads being held in such position in relation to the plane of revolution of the knotter bills, that the latter, on carrying out a three-quarter rotation grip behind the thread parts lying on one side of the knotter shaft and pass between the thread parts lying on the other side, so that two thread-loops are formed, whereupon during a further semi-rotation of the knotter bills the latter open and grip the end of one of the threads and finally cut off this end during a further quarter-rotation and clamps the same while the other thread end is cut off by scissors and finally the tie is pulled off the knotter bills.

The bight of the thread which is engaged to strip the tie off the knotter bills is preferably temporarily clamped, according to the invention, during the stripping operation, and the pull is exerted by means of a separate element moved against the thread between the clamp and the knotter bills.

The employment of knotter bills, or the construction employing coordinated thread slits and clamps, for tying a weaver's knot, according to earlier practice, depended on the condition, that the ends of the torn thread had to be laid in the knotter mechanism pointing in the same direction, in order to produce the knot. If one had tried to form a weaver's knot in the usual manner of operation, with ends of the thread point-

ing to different sides of the knotter shaft, a tie in the form of a weaver's knot would occur, but the ends to be pulled to tighten the knot would then be lying so that the knot would not be self-checking but would untie again when a pull should be exerted upon the knotted thread.

An embodiment of the invention is illustrated by way of example in the accompanying drawing, in which

Figs. 1 to 5 are diagrammatic views of a knotter device and threads, showing the main phases of the tying procedure,

Figs. 6 and 7 show the knotter in a central section approximately on line VI—VI of Fig. 9, its elements being in different positions,

Fig. 8 shows a partial top plan view, in the direction of the arrow VIII in Fig. 6,

Fig. 9 is a vertical transverse sectional view on the line IX—IX of Fig. 6, showing the mounting of the pivot bolt of the stripping member,

Fig. 10 is a detail vertical section on the line X—X of Fig. 7, showing the final step of the knotting procedure.

The knotter mechanism is mounted between two side walls 1 and 2 having a general shape common in knotters. The knotter may be supported upon an arm 3 of a carriage, for example, by means of a transverse plate 34 fixed to the arm 3 by screws 35. A knotter shaft 4 is journaled at its rear end in the plate 34 and at its front end in a bearing 36 carried by a crossbar 37 (Fig. 8). The front end of the knotter shaft 4 is bent away at approximately a right angle to form one of the knotter bills 38. The other knotter bill 39 is pivoted to the shaft 4 at 40. The knotter bill 39 has a tail portion 5 which is received within a cam ring 30, forming part of the crossbar 37, the cam ring being positioned eccentrically with respect to the axis of the knotter shaft 4. Thus the pivoted knotter bill 39 is oscillated as the knotter shaft 4 rotates. A shear blade 6 is fixed to the knotter shaft 4 and coacts with the bill 5 to sever one of the thread ends in customary manner.

The driving part of the knotter shaft 4 is in the form of a flat bar twisted into a screw and is engaged by the upper end of an actuating lever 7 which lies flat against the bar 4, as shown in Fig. 9. The actuating lever 7 is pivoted to a shaft 23 supported between the side walls 1 and 2. Counterclockwise rocking of the actuating lever 7 causes the knotter shaft 4 to execute a forward rotation of at least one and one half revolutions and the clockwise rocking of actuating lever 7 back to starting position causes a reverse move-

ment of the shaft 4 of the same extent. The two extreme positions are represented in Figs. 6 and 7.

A stripping hook 8 is fixed to a bolt 22 rotatably mounted in a bearing 45 on the side wall 2 (Fig. 9). A coil spring 21 on the bolt 22 is anchored at its right end to the bearing 45 and at its left end to the shoulder of bolt 22 and tends to hold the stripping hook 8 normally in the position shown in Fig. 6. A lug 46 on the actuating lever 7 is adapted to engage a cam 8a on the stripping hook 8 as the actuating lever nears the end of its forward movement, throwing the stripping hook down to the position shown in Fig. 7. In this position of the stripping hook a pin 20 thereon, of angular cross section, is engaged by a retaining member in the form of a pawl 19 pivotally supported on shaft 23 and urged downward by a spring 24 toward a stationary pin 48 on the side wall 2. The retaining pawl 19 is released from pin 20 toward the end of the return movement of the actuating lever 7, by engagement of the latter with a lug 49 on the upwardly extending arm of the pawl 19.

A deflecting bar 11 is rockably mounted on a transverse shaft 10, and has at its front end a notch 12 to coat with one of the thread ends in a manner to be described. At its rear end the deflecting bar has a cam surface 11a coacting with a pin 9 on the actuating lever 7, to cause a rocking movement of the deflecting bar near the end of the movement of the actuating lever.

Pivottally supported on a transverse shaft 50 is a notched bar 14 having a horn 31 to position two of the thread parts in a manner to be described. The notched bar 14 is extended at 51 (Fig. 8) in the form of a bail and at the end of this bail is a blade 52 forming part of a shears S, the other blade 53 of which is constituted by one end of a spring bail 15 fixedly mounted on the shaft 50. Also mounted on the shaft 50 is a plate comprising a clamping jaw 16 which coacts with the horn 32 of the notched bar 14 to clamp a part of one of the threads in a manner to be described. The plate bearing the clamping jaw 16 has a downwardly extending lug 16a which is normally held against a stop pin 18 by a coil spring 17, one end of which is hooked over the lug 16a, while the other end is hooked into the blade 52 of the bail 51. An arm 54 of the notched bar 14 has a slotted end 55 in which a pin 13 on the deflecting bar 11 engages.

The side plate 1 is provided with a horn 31 between two notches 31a and 31b, which are adapted to hold parts of the two threads in a manner to be described. The horn 31 is omitted from Fig. 6 to avoid confusion and the contour of the side wall 1 is consequently indicated in dot and dash lines.

The knotter is operated to tie a weaver's knot in the following manner:

With the mechanism standing in the normal position shown in Fig. 6, the two threads to be tied together are laid across the knotter shaft 4 behind the knotter bills 38, 39, uncrossed, with their ends extending in opposite directions from the knotter shaft, as shown in Fig. 1. The first thread, b, d, is laid in position with its bight b between the horn 32 and the clamp jaw 16 and its end d placed in the notch 31a and between the blades of the shears S. The second thread, a, c, is laid with its bight in the notch 31b and its end behind the horn 32. It will be observed that the bight b and end d of the first thread are both extended forward of the plane of revolution x-y of the knotter bills, while the end c of the second thread is extended forward of said plane of revo-

lution and the bight a of the second thread is extended rearward of the plane of revolution. Therefore, when the knot forming device, comprising the knotter shaft 4 and knotter bills 38, 39, executes its first quarter revolution (Fig. 2) the knotter bills engage over the bight b of the first thread and the end c of the second thread, while on the next half revolution (Fig. 3) the knotter bills pass between the end d of the first thread and the bight a of the second thread. This causes a crossed loop to be formed in the first thread around the knotter bills and an uncrossed loop to be formed in the second thread. The knotter bills are open during the first part of their first revolution (Fig. 2), but this is without significance, because no part of the threads is embraced by them at the time. During the next half revolution following the position shown in Fig. 3 the knotter bills are cammed open and arrive at the position shown in Fig. 4. Meanwhile, the pin 9 of the actuating lever 7 has reached the left end of the cam surface 11a and has rocked the deflecting bar 11 up from its position shown in Fig. 6. The thread end c lying in the notch 12 is thrust over into the plane of revolution of the knotter bills and thus in position to be grasped by the latter, as indicated in Fig. 4. The rocking of the deflecting bar 11 causes the notch bar 14 to be rocked up against the clamp bar 16, thus clamping the bight b of the first thread. Also, the blade 52 of the shears S is moved up and severs the end d of the first thread. Finally, the stripping hook 8 swings down, under the action of the actuating lever upon its cam 8a, and engages the bight b of the first thread between the clamp 14, 16, and the knotter bills. Upon further movement of the hook 8 the loop of the first thread is stripped off the knotter bills, which have meanwhile turned down to the position shown in Fig. 4, and thus over the end c of the second thread held in the grasp of the knotter bills. The end c and the bight b are held by the knotter bills and the clamp 14, 16, while the stripping hook 8 draws the knot tight. The outer part of the end c is severed by the shear blades 5 and 6 as the knotter bills close.

At the lower limit of its movement the stripping hook 8 is caught by the retaining pawl 19 and held there during most of the return movement of the other parts of the knotter mechanism. As the actuating lever 7 approaches its normal position it engages the lug 49 of the retaining pawl 19 and releases the stripping hook 8, which is thrown up to the position of Fig. 6 by its spring 21.

Although the form of construction of the knotter as shown is intended in the first instance for winding frames, the invention is not limited thereto, but may be applied anywhere in textile machines, when thread ends have to be knotted mechanically, as for instance also in warping machines.

What I claim as my invention and desire to secure by Letters Patent of the United States is:

1. In a mechanism for tying together two threads in a weaver's knot, a knot forming device comprising a rotary knotter shaft and knotter bills extending laterally therefrom so as to travel in a plane of revolution perpendicular to the axis of the knotter shaft as the latter rotates; means located at opposite sides of said knotter shaft for holding the ends and bights of two threads laid across said knotter shaft behind said knotter bills, with their ends extending in opposite directions from said knotter shaft; said holding means comprising means to hold the end and the bight of

the first thread extended forward of said plane of revolution on opposite sides of said knotter shaft, means to hold the end of the second thread extended forward of said plane of revolution adjacent the bight of said first thread, and means to hold the bight of said second thread extended rearward of said plane of revolution on the same side of said knotter shaft with the end of said first thread; means to revolve said knot forming device through at least one and one half complete revolutions in such direction that the knotter bills thereof first engage over the bight of said first thread and the end of said second thread, then pass between the end of said first thread and the bight of said second thread whereby said first thread is formed into a crossed loop and said second thread is formed into an uncrossed loop on said knotter bills; means to hold said knotter bills open during a part of their movement following their first complete revolution and then to close them; deflecting means to move the end of said second thread over said uncrossed loop and into said plane of revolution, so as to be grasped by said knotter bills during said last-mentioned portion of their movement; and means to strip said loops from the knotter bills, so that said crossed loop passes over the end of said second thread held in the grasp of the knotter bills.

2. A knot tying mechanism as described in claim 1, wherein clamping means are provided to engage the bight of said first thread and said stripping means is adapted to engage the bight of said first thread between said clamping means and said knotter bills.

3. In a mechanism for tying together two threads in a weaver's knot, a knot forming device comprising a rotary knotter shaft and knotter bills extending laterally therefrom so as to travel in a plane of revolution perpendicular to the axis of the knotter shaft as the latter rotates, means located at opposite sides of said knotter shaft for holding the ends and bights of two threads laid across said knotter shaft behind said knotter bills, with their ends extending in opposite directions from said knotter shaft, said holding means comprising a side wall at one side of said knotter shaft having two notches therein adapted to receive, respectively, the end of the first thread and the bight of the second thread and to hold the same extended divergently from said knotter shaft forward and rearward, respectively, of said plane of revolution, said holding means also comprising a clamping device, one member of which is provided with a horn for positioning the bight of said first thread and the end of said second thread so that both extend forward of said plane of revolution; means to revolve said knot forming device through at least one and one half complete revolutions in such direction that the knotter bills thereof first engage over the bight of said first thread and the end of said second thread, then pass between the end of said first thread and the bight of said second thread, whereby said first thread is formed into a crossed loop and said second thread is formed into an uncrossed loop on said knotter bills; means to hold said knotter bills open during a part of their movement following their first complete revolution and then to close them; deflecting means to move the end of said second thread over said uncrossed loop and into said plane of revolution so as to be grasped by said knotter bills during said last-mentioned portion of their movement; means to close said clamping means upon the bight of said first thread as said deflecting means is operated; and means acting upon the bight of

said first thread between said clamping means and said knotter bills to strip said loops from the knotter bills, so that said crossed loop passes over the end of said second thread held in the grasp of the knotter bills.

4. In a mechanism for tying together two threads in a weaver's knot, a knot forming device comprising a rotary knotter shaft and knotter bills extending laterally therefrom so as to travel in a plane of revolution perpendicular to the axis of the knotter shaft as the latter rotates; means located at opposite sides of said knotter shaft for holding the ends and bights of two threads laid across said knotter shaft behind said knotter bills, with their ends extending in opposite directions from said knotter shaft; said holding means comprising means to hold the end and the bight of the first thread extended forward of said plane of revolution on opposite sides of said knotter shaft, means to hold the end of the second thread extended forward of said plane of revolution adjacent the bight of said first thread, and means to hold the bight of said second thread extended rearward of said plane of revolution on the same side of said knotter shaft with the end of said first thread; actuating means having a forward and reverse movement to revolve said knot forming device at least one and one half complete revolutions and back to starting position, said knot forming device being revolved during the forward movement of said actuating means in such direction that the knotter bills thereof first engage over the bight of said first thread and the end of said second thread, then pass between the end of said first thread and the bight of said second thread, whereby said first thread is formed into a crossed loop and said second thread is formed into an uncrossed loop on said knotter bills; means to hold said knotter bills open during a part of their movement following their first complete revolution and then to close them; deflecting means moved by said actuating means to thrust the end of said second thread over said uncrossed loop and into said plane of revolution, so as to be grasped by said knotter bills during said last-mentioned portion of their movement, stripping means operated by said actuating means to strip said loops from the knotter bills, so that said crossed loop passes over the end of said second thread held in the grasp of the knotter bills, retaining means adapted to catch said stripping means and holding the same in actuated position, and means whereby said retaining means are released by said actuating means just before the latter completes its reverse movement.
5. In a mechanism for tying together two threads in a weaver's knot, a knot forming device comprising a rotary knotter shaft and knotter bills extending laterally therefrom so as to travel in a plane of revolution perpendicular to the axis of the knotter shaft as the latter rotates, means located at opposite sides of said knotter shaft for holding the ends and bights of two threads laid across said knotter shaft behind said knotter bills, with their ends extending in opposite directions from said knotter shaft; said holding means comprising a side wall at one side of said knotter shaft having two notches therein adapted to receive, respectively, the end of the first thread and the bight of the second thread and to hold the same extended divergently from said knotter shaft forward and rearward, respectively, of said plane of revolution, said holding means also comprising a clamping device, one member of which is provided with a horn for positioning the bight of said first thread and the end of said second thread so that both extend forward of said plane of revolution; means to revolve said knot forming device through at least one and one half complete revolutions in such direction that the knotter bills thereof first engage over the bight of said first thread and the end of said second thread, then pass between the end of said first thread and the bight of said second thread, whereby said first thread is formed into a crossed loop and said second thread is formed into an uncrossed loop on said knotter bills; means to hold said knotter bills open during a part of their movement following their first complete revolution and then to close them; deflecting means to move the end of said second thread over said uncrossed loop and into said plane of revolution so as to be grasped by said knotter bills during said last-mentioned portion of their movement; means to close said clamping means upon the bight of said first thread as said deflecting means is operated; and means acting upon the bight of

thread so that both extend forward of said plane of revolution; means to revolve said knot forming device through at least one and one half complete revolutions in such direction that the knotter bills thereof first engage over the bight of said first thread and the end of said second thread, then pass between the end of said first thread and the bight of said second thread, whereby said first thread is formed into a crossed loop and said second thread is formed into an uncrossed loop on said knotter bills; means to hold said knotter bills open during a part of their movement following their first complete revolution and then to close them; deflecting means to move the end of said second thread over said uncrossed loop and into said plane of revolution so

15

as to be grasped by said knotter bills during said last-mentioned portion of their movement; means to close said clamping means upon the bight of said first thread as said deflecting means is operated; a cutting device comprising two shearing blades positioned to embrace the end of said first thread between said side wall and said knotter bills, one of said shearing blades being connected to said clamping means so as to be operated to shear the end of said first thread as said clamping means are closed, and means to strip said loops from the knotter bills, so that said crossed loop passes over the end of said second thread held in the grasp of the knotter bills.

STEFAN FÜRST.
